118,504

DESIGN FOR A COMBINED LAMP AND RADIO RECEIVING SET

John J. Punke, Detroit, Mich., assignor to Daniel J. Crowley, Grosse Pointe, Mich.

Application October 23, 1939, Serial No. 87,827

Term of patent 14 years

To all whom it may concern:

Be it known that I, John J. Punke, a citizen of the United States of America, residing at Detroit, in the county of Wayne and State of Michigan, have invented a certain new, original, and ornamental Design for a Combined Lamp and Radio Receiving Set, of which the following is a specification, reference being had therein to the accompanying drawing, forming a part thereof, wherein, my new design of a combined lamp and radio receiving set is illustrated by a front elevational view.

The design of the combined lamp and radio

receiving set is substantially symmetrical about its vertical axis in that the side opposite the side shown in the drawing is the same in appearance, with the exception that the opening exposing the graduated dial is omitted and also with the exception that the indicia on the reverse side varies to indicate the different radio receiving stations.

I claim:

The ornamental design for a combined lamp and radio receiving set, substantially as shown and described.

JOHN J. PUNKE.
